DESCRIPTION

FIG. 1 is a front perspective view of a first embodiment of the liquid dispensing device;

FIG. 2 is a front elevational view of the first embodiment; FIG. 3 is a right side view of the first embodiment, the left side being a mirror image thereof;

FIG. 4 is a rear view of the first embodiment;

FIG. 5 is a top view of the first embodiment;

FIG. 6 is a bottom view of the first embodiment;

FIG. 7 is a front perspective view of a second embodiment of the liquid dispensing device;

FIG. 8 is a front elevational view of a second embodiment; FIG. 9 is a right side view of the second embodiment, the left side being a mirror image thereof;

FIG. 10 is a rear view of the second embodiment;

FIG. 11 is a rear view of the second embodiment;

FIG. 12 is a bottom view of the second embodiment;

FIG. 13 is a front perspective view of a third embodiment of the liquid dispensing device;

FIG. 14 is a front elevational view of the third embodiment; FIG. 15 is a top view of the third embodiment; and,

FIG. 16 is a bottom view of the third embodiment.

The right, left and rear views of the third embodiment are the same as shown and described for FIGS. 3 and 4. Finally, the various design features of the three embodiments may be interchanged with one another.

The elements shown in broken lines are for environmental purposes and relate to elements which do not form part of the claimed invention.
